(57) CLAIM

The ornamental design for a media player charging sling, as shown and described.

DESCRIPTION

FIG. 1 is perspective view of a media player charging sling showing my new design in environmental use;

FIG. 2 is a perspective view thereof;

FIG. 3 is a front elevational view thereof;

FIG. 4 is a right-side elevational view thereof, the left side being a mirror image;

FIG. 5 is a top plan view thereof; and,

FIG. 6 is a bottom plan view thereof.

The broken lines in the drawings are included for illustrative purposes only and form no part of the claimed design.
